ELECTRON TUBE

Samuel B. Rubinstein, New York, N. Y.

Application July 25, 1928, Serial No. 295,164

8 Claims. (Cl. 250—27.5)

My invention relates broadly to electron tubes and more particularly to a construction of electron tube energized by power derived from the usual house lighting mains without the employment of primary or secondary batteries.

One of the objects of my invention is to provide a construction of electron tube known as the auxiliary heater type where the elements are so positioned within the tube as to reduce the effect 10 of noise inherent in the power supply system upon the sensitive sound reproducing system in which the tubes are connected.

Another object of my invention is to provide a construction of electron tube having an electron 15 emitter energized by power derived from the usual house lighting mains wherein the filament is substantially electrostatically and electromagnetically shielded from the grid and plate electrodes within the tube for avoiding the reproduction 20 of alternating current line hum or direct current generator ripple which may be present in the power supply system.

A further object of my invention resides in the construction of an electron tube of the auxiliary 25 heater type wherein the heated filament is formed by a pair of substantially solenoidal shaped windings extending in parallel axes and surrounded by cylindrical members bearing an electron emitting coating on the exterior thereof maintained 30 in position with respect to a grid and plate electrode for magnetically and electrostatically isolating the filament from the grid and plate electrodes.

Still another object of my invention is to provide 35 a construction of electron emitter for an electron tube of the auxiliary heater type wherein a heated filament is carried by a pair of parallel extending hollow tubular members with concentrically disposed cylindrical members around the 40 filament whereby said cylindrical members may be heated by radiation and convection to an electron emitting temperature.

Still further objects of my invention reside in the construction and arrangement of parts with- 45 in an electron tube of the auxiliary heater type and the arrangement of emitter for concentrating the electromagnetic field established by the passage of heating current through the filament electrode in a zone substantially isolated from 50 the grid and plate electrodes within the electron tube preventing interference from line variation upon the operation of the electron tube.

Other and further objects of my invention re- 55 side in the construction and arrangement of parts for an electron tube of the auxiliary heater type

as set forth more fully in the specification hereinafter following by reference to the accompanying drawings, in which:

Figure 1 shows a circuit arrangement diagrammatically illustrating the application of the electron tube structure of my invention as a detector; Fig. 2 is an enlarged diagrammatic view of the electron emitting structure employed in the electron tube of my invention; Fig. 3 is a perspective view of the shield and electron emitting electrodes; Fig. 4 is a view of one of the spacer members used for locating the leads of the electrodes within the electron tube structure; Fig. 5 is a cross-sectional view taken through the electron tube structure of my invention; Fig. 6 is a wiring 10 diagram of a complete radio broadcast receiving apparatus employing electron tubes of the structure covered by my invention; Fig. 7 is a view of one of the electron emitting members employed 15 in the electron emitter structure; Fig. 8 is a cross-sectional view taken on line 8—8 of Fig. 7 through the electron emitter; Fig. 9 is a diagrammatic view illustrating the arrangement of leads to the electrodes within the tube structure; Fig. 10 is a fragmentary view of the insulated support for 20 the leads to the tube electrodes; Fig. 11 is a plan view of the base for the electron tube of my invention; Fig. 12 is a side view of the base illustrated in Fig. 11; Fig. 13 is a theoretical view 25 showing the distribution of the magnetic lines of force comprising the magnetic field which surrounds the electrodes in the tube structure of my invention; and Fig. 14 is a perspective view showing 30 more clearly the arrangement of parts of the electron emitter employed in the tube structure 35 of my invention.

Referring to the drawings in detail, I have illustrated the electron tube structure of my invention connected in a radio receiving circuit in Figure 1 where reference character 1 designates the antenna, 2 the ground connection, 3 the primary winding of a coupling transformer, 4 the secondary winding of the coupling transformer, and 5 designates a variable condenser for tuning the secondary system 4. The electron tube structure of my invention is enclosed within an evacuated vessel 6 and includes a pair of vitreous tubes 7 apertured throughout their entire length. The vitreous tubes 7 are surrounded by cylindrical members 8 which are arranged 50 within the evacuated envelope 6 in definite relation to the control electrode 9 and plate electrode 10. In the diagram of Figure 1, the grid electrode 9 is connected at 16 through a lead including grid condenser 23 shunted by grid leak 22 55

with one side of the tuned circuit 4—5. The plate electrode 10 is connected through lead 24 and telephones 19 with high potential source represented at 20 which is in turn connected 5 through lead 15 with the cylindrical members 8 and with the opposite side of the tuned circuit 4—5. As more clearly shown in Figs. 2, 7, 13 and 14, the vitreous tubes 7 provide supports for the filament 11 which is wound thereon substantially 10 in the nature of a solenoidal winding clamped at the top and bottom by two collars 18 which prevent the filament from unraveling. The ends of the filament, that is the portions extending past the collars 18, are wound around the upwardly extending portions 12a and 12b of the bridge member 12 which provides a connection between the two solenoidal windings. The opposite ends of the filaments 12 connect to the leads 14a and 14b which pass through the glass stem 20 of the tube represented at 28 in Fig. 11 in the relative positions shown. The cylindrical members 8 which surround the solenoidal filament windings 11 are connected at opposite ends through conductors 13 and 17 providing a rigid 25 structure as shown more clearly in Fig. 3 arranged to be supported from extending members 30 and 15 within the tube assembly. The lighting mains of a residence may be connected directly at the terminals 21a and 21b for energizing the filament 30 11. The electrodes within the tube structure are assembled as shown in Fig. 5, wherein insulated members 25 and 26 serve as spacers for the leads extending to the electrodes. The plate electrode is designated at 10 substantially in the form of a 35 cylindrical member supported on conductors 27 anchored at opposite ends in insulated members 25 and 26. One of the conductors continues, as represented at 24 in Fig. 11 to provide a plate lead to the electron tube. The grid electrode 9 40 surrounds the electron emitter and is disposed adjacent the interior of the plate electrode and is formed by a spirally wound conductor on wire supports 29 which extend between insulated members 25 and 26, one of the conductors extending as represented at 16 to provide a connection 45 to the grid electrode. The electron emitter is centered within the tube structure by means of member 30 extending into insulated member 26, and by the extension of member 12a into the 50 insulated member 26, the lead to the electron emitter 8 extends through the stem of the tube as represented at 15. The leads with the ends of the filament 11 extend to the stem of the tube as represented at 14a and 14b. The members 12a 55 and 12b may be suitably secured to the ends of the bands 18 as illustrated more clearly in Fig. 8.

The tube structure may be mounted in an insulated support 49 represented in Figs. 11 and 12 with power terminals 51, 52, 53 and 54 protruding 60 therefrom. The bayonet slot pin member 50 is positioned in one side of the adaptor to permit the tube to be inserted readily into the standard socket face. A shelf-like member 57 extends from the top of the base 49 and carries binding posts 65 55 and 56 thereon through which connections may be established with the lighting circuit and thence to the filament terminals in the electron tube.

In Fig. 6, I have illustrated the application of the tube of my invention to a radio broadcast receiving set constituted by two stages of radio frequency amplification at 31—32 with coupling transformer 36 therebetween, a detector tube 33 coupled to the output of the radio frequency amplification system through transformer 37 and 70 audio frequency amplification stages constituted

by electron tubes 34 and 35 connected through coupling transformers 38 and 39. The primary winding of transformer 38 may be shunted by bypass condenser 40. The filament heating circuit is completed through leads 47 and 48. Terminals 41, 42, 43, 44, 45 and 46 are provided to impress the required operating potential on the remaining circuits of the several electron tubes in the receiving system. 5

The electron tube structure of my invention is provided with that kind of an auxiliary heater which will permit the interior walls of the electron emitting members 8 to be heated by radiation and convection heat currents from filament 11. The vitreous tubes 7 have a hollow interior throughout their length to permit the uniform distribution of convection currents for heating the cylindrical members 8. 10 15

The heat radiated and that received from the convection currents is absorbed by the members 20 8 composed of concentric cylindrical nickel tubes which are coated on the outside surfaces only, by a radio-active or electron emitting salt of the barium, strontium and calcium group. The heat received by the members 8 is sufficient to make 25 the radio-active material emit electrons which bombard the anode 10 under control of grid 9. 25

Either alternating or direct current may be supplied from the house lighting mains for energizing the filament windings 11 and it is unnecessary to interpose a transformer in the circuit. 30

It will be observed in Fig. 13 that the magnetic field set up by the passing of current through the solenoidal filament windings 11 represented by dotted lines 60 are concentrated within electron 35 emitter, turning upon itself through the hollow cores of the windings 11. The independent magnetic field of each solenoidal winding 11 may take the path represented at 60a and 60b but this path is substantially confined within the cylindrical 40 members 8 thus preventing leakage of the magnetic field through the grid and plate electrodes and the setting up of undesirable noises in the 45 circuits connected to the electrodes. 50

In order to further prevent the setting up of 45 noises in the circuits of the electron tube system, I extend the cylindrical members 8 with respect to the filament windings 11 for a longer length with respect to the length of the grid 9 to substantially shield the grid. 50

The electron emitter is maintained at ground 55 potential so that induced voltages on the cylindrical members 8 may be by-passed with respect to the other electrodes of the tube. The lead 16 extending from the grid is shielded from the high voltage lines as illustrated in Fig. 11 by spacing this lead therefrom with the grounded lead 15 interposed therebetween. This same practice is followed at the upper end of the support for the tube electrodes where the grid support 16 is spaced from the high voltage source existent at 12a by the grounded lead 30 or spaced at a substantial distance as represented by the spacial 60 relation between the lead 29 and the lead 12a along the insulated member 26. 65

The tube construction of my invention has been found to be extremely practical in its construction, manufacture and operation, and while I have described a preferred embodiment of my invention, I desire that it be understood that modifications may be made and that no limitations upon my invention are intended other than are imposed by the scope of the appended claims. 70

What I claim as new and desire to secure by Letters Patent of the United States is as follows: 75

1. An electron tube of the auxiliary heater type comprising a pair of parallel extending tubular members each providing an insulated core for the support of a filament winding thereon, bands 5 encircling the extremities of said tubular members and establishing electrical connection with the ends of the filament, a bridge member interconnecting the bands at the upper extremities of said tubular members, and a pair of cylindrical members encircling said tubular members and carrying electron emitting coatings thereon.

2. An electron tube of the auxiliary heater type comprising a pair of hollow cylindrical members of vitreous material, a filament spirally wound 15 on each of said members, means encircling and mechanically interconnecting the upper extremities of said members for fixing said members in predetermined spacial relation and providing a series electrical connection for the filaments on 20 said vitreous members, conductive ring devices encircling the lower extremities of said cylindrical members and providing bonding connections for the ends of said filament, and a pair of separate cylindrical members surrounding said tubular 25 members and having electron emitting surfaces thereon.

3. An electron tube of the auxiliary heater type comprising a pair of vitreous tubular members, means for mounting said members in parallel 30 relationship spaced one from the other comprising individual means embracing and supporting each of said members at the lower extremities thereof and conductive means embracing the upper extremities of said members and interconnected for maintaining the spacial relation 35 of said members at the upper extremities thereof, a filament wound along said members, a pair of cylindrical elements enclosing each of said tubular members, and grid and plate electrodes concentrically positioned around said cylindrical 40 elements, said cylindrical elements being substantially longer than said grid and plate electrodes, whereby said grid and plate electrodes are substantially shielded from the effects of said filament.

4. In an electron tube of the auxiliary heater type, an electron emitter including a heater member consisting of a pair of filamentary windings disposed on spaced parallel axes with respect to 50 each other for concentrating the effects of the magnetic fields thereof within a central zone in said electron tube, grid and plate electrodes concentrically disposed around said heater member, electron emitting surfaces enclosing and spacially related to each of the filamentary windings constituting said heater member and operating 55 to emit electrons under control of said heater member and shielding said grid and plate electrodes from the magnetic effects of said filamentary windings and means at each end of said

electron emitting surfaces for maintaining said pair of filamentary windings in predetermined relation to said electron emitting surfaces.

5. In an electron tube of the auxiliary heater type, an electron emitter comprising a pair of filamentary windings disposed in parallel relation one with respect to the other, cylindrical members enclosing said filamentary windings and spaced therefrom in concentric relation thereto, each of said cylindrical members having 5 electron emitting coatings thereon, means connected at opposite extremities of each of said cylindrical members for maintaining said cylindrical members at equi-potential and means extending laterally of said pair of filamentary windings for maintaining said windings centrally of 10 said cylindrical members.

6. An electron emitter for vacuum tubes of the auxiliary heater type comprising a pair of parallel extending tubular members, heating filaments 20 wound on said tubular members, means embracing opposite ends of said tubular members, a bridge member extending between said means at one end of said tubular members for supporting said tubular members at their upper extremities 25 in fixed spacial relation and providing an electrical connection between said heating filaments, terminal connections between the ends of the heating filaments and the means embracing adjacent ends of said tubular members, and a pair of 30 cylindrical members surrounding said tubular members in spaced relation to the heating filaments, said tubular members having electron emitting surfaces thereon.

7. A cathode structure for electron tubes comprising a rod member of insulating material, a cathode member surrounding said rod member, a heater filament spirally wound on said rod member, clamping devices engaging opposite ends of said rod member, a connection between the 35 ends of said heater filament and said clamping devices, and terminals and supporting means extending from said clamping devices for centering said rod member in spacial relation to said cathode member.

8. A cathode structure for electron tubes comprising a tubular cathode member, a rod of insulating material extending axially through said tubular cathode member, metallic bands embracing opposite ends of said rod member, means extending from said metallic bands for centering said rod member with respect to said tubular cathode member and supporting said rod member with respect thereto, and a spiral heater filament mounted on said rod member and having its 50 opposite ends electrically connected to the respective metallic bands at opposite ends of said rod member.

SAMUEL B. RUBINSTEIN.
